UNITED STATES PATENT OFFICE.

CASSIUS M. WHITE AND ALFRED E. SMALL, JR., OF DENTON, MARYLAND.

SUN CURTAIN FOR AUTOS.

Application filed April 18, 1922. Serial No. 555,020.

To all whom it may concern:

Be it known that we, CASSIUS M. WHITE and ALFRED E. SMALL, Jr., citizens of the United States of America, residing at 5 Denton, in the county of Caroline and State of Maryland, have invented certain new and useful Improvements in Sun Curtains for Autos, of which the following is a specification.

10 This invention relates to sun curtains or shields for use on motor vehicles and particularly to shields which are adapted to be mounted upon the top-supporting bows of the vehicle and so arranged that they 15 may be readily adjusted to effectively shield the occupants from the glare of the sun or from wind or rain.

The principal feature of our invention resides in a simple and effective support 20 for the curtain which will permit of angular adjustment to suit conditions without the manipulation, loosening or removal of the securing devices.

Another feature resides in a construction 25 of curtain support in which the curtain is maintained by a yielding pivotal connection in any of its adjusted positions within the range of its movement.

A further feature resides in the extreme 30 simplicity of construction of the curtain which will permit of its production at a comparatively low cost.

A further feature resides in the construction 35 of a modified or emergency hanger 35 where the curtain is to be applied to a bow of the type where said bow does not extend entirely to the rear of the top.

In the accompanying drawings,

40 Figure 1 is a front elevation of the curtain illustrating in dotted lines a vehicle top bow and the manner of application of the curtain support thereto;

Figure 2 is a horizontal sectional view on the line 2—2 of Figure 1, looking in the 45 direction of the arrows, and showing in dotted lines, the curtain swung to one of its adjusted positions;

Figure 3 is a central vertical sectional view taken thru one of the curtain supports;

Figure 4 is a horizontal sectional view on the line 4—4 of Figure 3 looking in the direction of the arrows;

Figure 5 is a front elevation of the curtain frame and

Figures 6 and 7 are respectively side and front views of a modified form of support or emergency hanger.

Referring more particularly to the drawings by numerals of reference 2 indicates 60 one of the top bows of a vehicle top of ordinary construction, and to which is attached the hereinafter described sun curtain and rain shield.

The shield or curtain designated generally by the numeral 4, comprises a preferably rectangular frame formed of light yet substantially strong metal rods 6, over which is stretched and secured by stitching or other suitable means, a fabric covering 70 8 of a material similar to that of which the vehicle top is formed.

The covering 8 is preferably constructed in the form of a pocket into which the frame is inserted so as to not only maintain the 75 fabric taut, but also to entirely cover the metal frame, thus avoiding any unnecessary exposure of metallic parts. After the frame has been inserted into the pocket the open side is stitched along a line adjacent and outside the inner frame member, the covering being extended to provide flaps 10 which assist in the exclusion of rain or wind.

Adjacent its upper and lower portions, 85 the frame is provided with transverse supporting bars 12 having portions 14 which extend thru the stitched side of the covering and pass respectively thru openings in the side flanges 16 of channel members 18, 90 the extensions 14 upon their extreme outer ends being threaded to receive nuts 20, which when turned home bind the inner frame member against the inner side flanges 16. 95

Formed integral with the flanges 16 of each of the channel members 18 is a plate 22, the outer face of which is provided with an annular series of radial corrugations or flutes 24 which co-operate with a similarly 100 formed face on a plate 26 rigid with an arm or bracket 30 carried respectively by an upper and lower top bow clamping collar 32.

The co-operating faces of the respective 105 channel and bracket members 18 and 30 are maintained in engagement thru the medium of a pivot pin or bolt 34 passing vertically thru the axis of said members, said pin upon its threaded lower end having a nut 110

36, between which and the lower face of the plate 26 is interposed a lock washer 38. It will be observed upon reference to Figure 3, that the plate 26 is slightly dished as at 40 which permits of a sufficient yielding of said plate when the shield is swung or adjusted upon its pivot to allow the corrugations of the opposing faces of the plates 22 and 26 to override one another and to snap back into normally locked position.

In the form shown in Figures 6 and 7, I have illustrated a modified form of support or what may be termed an emergency hanger for use with automobile tops where the top 15 bow does not extend thruout the length of the top. As here illustrated the bow is indicated at 50, and the hanger or support for the sun curtain is indicated generally at 52 and comprises an angular metal strip the 20 upper or horizontal arm 54 of which is clamped at 55 to said bow 50, the lower end of the vertical portion 56 being suitably clamped to the bow 50 at 59. The intermediate portion of the member 56 is in 25 the nature of a disk 60 having on its rear face, an annular series of ribs or corrugations 61 which co-operate with a similarly formed face of a rotary or adjustable disk or plate 62, the parts being maintained in 30 assembled relation thru the medium of a bolt 64, upon the inner end of which is a nut 65, which confines a channel member 66 similar to the channel member 18 in Figure 1.

35 Adjustment of the disks relatively to one another is secured by manipulation of a handle 70 on the outer end of the bolt 64.

The vertical webs of the channel member 66 are provided with registering openings 40 72 thru which passes one or the other members 14 of the sun shield to support the latter.

We claim:

1. A sun curtain or shield for automo-

biles comprising the substantially rectangular frame, a fabric covering secured over said frame, supporting bars extending transversely and adjacent the shorter sides of said frame, the free ends of said supporting bars extending beyond the longitudinal sides 45 of said frame, supports in which the free ends 50 of said supporting bars are mounted, the inner face of said supports being provided with serrations, brackets carried by the bow of a vehicle top, a plate carried by each of 55 said brackets, the inner faces of each plate being provided with serrations for cooperation with the serrations upon the inner faces of said supports, and means for pivotally mounting said supports on the plates of 60 said brackets, one of said plates being dished to yieldably maintain the serrated faces of the supports and plates in a set position.

2. A sun curtain or shield for automobiles comprising a frame, a fabric covering secured over said frame, supporting bars 65 extending transversely of said frame and having the free ends thereof extending beyond one side of said frame, supports in which said supporting 70 bars are mounted, said supports constituting a channel member and a plate at the lower end of said channel member and provided with serrations, brackets adapted to be clamped upon the bow of the vehicle top, 75 a plate carried by each of said brackets, means for pivotally mounting said supports on the plates of said brackets, said plates having their inner faces serrated for cooperation with the serrated faces of said 80 supports, the plates carried by the said brackets being dished for yieldably maintaining the serrated faces of said plates and supports in a set position.

In testimony whereof we affix our signatures.

CASSIUS M. WHITE.

ALFRED K. SMALL, JR.
